(57) **CLAIM**

The ornamental design for an electrodeless light fixture, as shown and described.

DESCRIPTION

FIG. 1 is a perspective view of an electrodeless light fixture according to the present invention;

FIG. 2 is a top view of an electrodeless light fixture according to the present invention;

FIG. 3 is a bottom view of an electrodeless light fixture according to the present invention;

FIG. 4 is a first side view of an electrodeless light fixture according to the present invention; and,

FIG. 5 is a second side view of an electrodeless light fixture according to the present invention.

The broken lines shown in the drawings are for the purpose of illustrating portions of the light fixture and form no part of the claimed design.
